SEPARATOR FOR ELECTRIC ACCUMULATORS

Gerardus Hendrikus Beusker, Arnhem, and Friedrich August Schneider, Venlo, Netherlands, assignors to Accumulatorfabriek "Varta" N.V., Venlo, Limburg, Netherlands, a limited-liability company of the Netherlands

Application May 14, 1956, Serial No. 584,523

13 Claims. (Cl. 136—145)

The invention relates to a separator for electric accumulators. Such separators are known in many forms. They sometimes consist of a number of independent layers lying against one another and consisting of various materials, such as wood, plastic, hard rubber, glass mat, etc.

The separator according to the invention provides an improvement of the known separators and is characterized in that it is composed of a combination of three elements or layers, there being an intermediate element or layer and two facing elements or layers applied to opposite sides of the intermediate element. One of the facing elements consists of a non-splitting filtering layer (such as a filter plate or filter cloth) with pores not greater than about 0.02 mm. The intermediate element or layer consists of a corrugated and perforated plate of plastic or hard rubber, and the other facing element or layer consists of a glass mat, said three elements being joined by sewing along at least one seam passing through a corrugation of the intermediate element.

The choice of this construction is based on the discovery that effective combination of a number of elements which are partly known *per se* results in several important advantages, which are to be described more in detail below.

The drawing illustrates, by way of example, a number of embodiments of separators according to the invention.

Fig. 1 is a cross-section and Fig. 2 a side elevation of a first embodiment, in which only the intermediate element is corrugated.

Fig. 3 is a cross-section through a second embodiment, in which both the facing filtering element and the intermediate element are corrugated.

Fig. 4 is a cross-section through a third embodiment, in which the separator is fitted with reinforcing needles.

Fig. 5 is a side elevation of the separator according to Fig. 4, in which the needles are constructed in a special manner.

Fig. 6 is a cross-section through a fourth embodiment, in which some of the corrugations of the intermediate element have a substantially rectangular cross-section.

Fig. 7 is a cross-section and Fig. 8 a side elevation of a fifth embodiment, in which two of the edges of the intermediate element are non-corrugated and non-perforated.

Fig. 7a is a cross section through a sixth embodiment, in which two of the edges of the facing filtering element have been folded about the non-corrugated adjacent edges of the intermediate element.

Figs. 9 and 10 are partial side elevations of a seventh and an eighth embodiment, in which one of the edges of the intermediate element is locally fitted with reinforcing members.

In all the figures corresponding parts have been designated by the same reference numerals.

In Figs. 1 and 2 the numeral 1 indicates the facing filtering element, 2 the intermediate element and 3 the other facing element. The facing filtering element 1 consists of a non-splitting filter plate with pores not greater

2

than about 0.02 mm. Suitable materials for this filter plate are acid-resistant microporous plastics on a polyvinyl chloride or polystyrene basis, microporous hard rubber, acid-resistant fabrics, fabrics on a polyamide and polyester basis, glass fabrics, and acid-resistant impregnated microporous materials, such as paper, paper reinforced with glass fibres, asbestos, and the like. As compared with wool, these materials have the advantage that they can easily be sewn to the other elements of the separator without being damaged. They have the further advantage over wood that they can be built in an absolutely dry condition, so that the separators become suited for use in so-called dry charged batteries.

The intermediate element 2 consists of a corrugated and perforated plate of an acid-resistant plastic, such as a plastic on a polyvinyl chloride basis, or a similar plate of hard rubber, both of which are also electrically non-conductive. The perforations made in it are designated in Fig. 2 by 4.

15 The other facing element 3 consists of a glass mat. This has a slightly smaller width than the elements 1 and 2. Although this is no absolute requirement, it has the advantage that when a separator designed in this way is being used in an accumulator, no mass particles from 20 the accumulator electrodes will deposit on the edges of the separator, so that the risk of short-circuits between the electrodes is minimized. Along the edges of the separator, owing to the smaller width of the glass mat 3 there are formed free spaces, through which during the charging 25 of the accumulator a strong flow of gas and liquid will pass, which will remove any mass particles that may be liberated.

The three elements 1, 2 and 3 of the separator have been joined by sewing along a number of seams 5, each 30 of which passes through and extends longitudinally along one of the corrugations of the intermediate element 2. The provision of such sewing seams is possible for a separator composed of the three elements described, without the risk of one or more of said elements splitting

35 during the sewing operation. By providing the sewn seams the three elements are under all circumstances kept firmly together in the right relative position, so that they cannot shift relative to one another either during the construction of an accumulator with the aid of a plurality of separators according to the invention, or during the 40 use of this accumulator. This not only simplifies the manufacture of the accumulator, but also enhances its durability.

In the separator according to Fig. 3 not only the intermediate element 2, but also the facing filtering element 1 is corrugated. The mutual distance of the corrugations is the same in both elements and the corrugations in element 1 are aligned with and hence nested within the corrugations of the element 2. The height 45 of the corrugations of the element 1 is less than one half the height of the corrugations of the element 2.

When in this way the element 1, too, is fitted with corrugations, the three elements of the separator are kept together even more effectively and firmly by the 50 seams 5. At the same time the degassing of the negative electrodes of the accumulator is improved to the extent that especially at low temperatures, e.g. —20° C., a considerably greater starting capacity is obtained.

The separator shown in Fig. 4 is provided with a number of spaced needles 6, which have been applied between the element 1 and the element 2, and each of which lies in a corrugation of the element 2. Said needles can be made of an acid-resistant plastic or of hard rubber.

55 The needles are of special advantage for separators 70 destined to be used in accumulators which during use are exposed to excessive vibrations and shocks, such as

motor and tractor batteries. The presence of the needles make it possible to pack the separators and electrodes of such accumulators tightly in the accumulator box, which greatly reduces the risk of damage to the accumulator electrodes, even during rough handling.

The needles 6 can be provided before or after the three elements of the separator have been sewn together. Under certain circumstances it may be advisable to fasten them to the corresponding corrugations of the intermediate element 2 and, if necessary, also to the facing filtering element 1, which may be done, for example, by means of an acid-resistant adhesive or by welding or sealing.

Fig. 5 shows a side elevation of the separator according to Fig. 4, provided with needles 6. At the bottom the needles extend beyond the separator, and they may serve to support the separator, when mounted in an accumulator, on the bottom of the accumulator box. Thus the firmness of the separators and accumulator electrodes mounted in said box is enhanced even further.

In the separator according to Fig. 6 and also Fig. 7a certain of the corrugations of the intermediate element 2, designated by 7, have a substantially rectangular cross-section and are not perforated, while the three elements 1, 2 and 3 of the separator are joined by sewing seams 5 along the corrugations 7.

This construction will lead to a separator which even at excessive operational temperatures, such as may occur e.g. in tropical regions, will never be crushed and keeps its original shape even under very unfavorable conditions. Moreover the three component elements 1, 2 and 3 are very firmly joined because at the spot of the sewing seams 5 the element 2 consists of non-perforated material and consequently is of great strength. This effect is enhanced even further if, as also shown in Fig. 6, in each substantially rectangular corrugation 7 of the element 2 is positioned i.e. nested a corrugation 8 of approximately equal height of the element 1. Owing to the coincidence of the corresponding corrugations 7 and 8 the sewing seams can be made more firmly 40 and the three elements are fixed exceptionally effectively in relation to one another.

In the separator according to Figs. 7 and 8 those two edges 9 of the element 2 which are parallel to the corrugations in this element are non-corrugated and non-perforated, while lying close against the element 1. Along these edges 9 the maximum possible space for the flow of gas and liquid is thus obtained. Moreover the risk of damage to the element 2 upon a number of separators and accumulator electrodes being packed in an 50 accumulator box is reduced.

In the separator according to Fig. 7a the edges 9 of the element 2 are non-corrugated and either perforated or non-perforated. The element 1 consists of a filter cloth, whose edges 13 have been folded about the edges 9 of the element 2 and fastened thereto. This fastening can be attained by using for the elements 1 and 2 suitable thermoplastic materials and welding or sealing each of the edges 9 of the element 2, by the application of heat, between the edge 13 of the element 1 and the remainder of this element. A suitable material for the element 1 is a filter cloth of polyester yarn, while a suitable material for the element 2 is a plastic on a polyvinyl chloride basis, such as solid polyvinyl chloride.

Figs. 9 and 10 show that one of the edges of the element 2 which are at right angles to the corrugations of said element can be fitted locally with a reinforcement 10, so as to make it possible, without risk of damage, for said edge to rest on an elevation 11 provided on the bottom 12 of the accumulator box. This support ensures a further improvement and a permanent effective position of all the separators in the accumulator box.

In Fig. 9 the reinforcement 10 consists of a strong acid-resistant material, e.g. plastic, which has been dou-

bled locally about the lower edge of the element 2 and can, if desired, be fastened thereto.

In Fig. 10 the reinforcement consists of a triangular part of the element 2 itself, which first extended downwards beyond the lower edge of said element and afterwards was doubled up. In this manner, too, a firm supporting member is formed, which rests on the elevation 11 of the bottom 12 of the accumulator box.

It is self-evident that the embodiments of the separator according to the invention as shown in the various figures can also be combined at need. Nor is the invention limited to the embodiments shown in said figures or the combinations thereof. Within the scope of the invention a great many variations are possible.

The separator according to the invention is particularly suited for accumulators to be stored in dry condition, or for so-called dry charged accumulators. Indeed, such accumulators—if they are to keep their capacity even during prolonged storage—after being mounted have to be perfectly free from moisture. This cannot be attained with wooden or wood-containing separators because wood cannot be rendered perfectly dry without splitting, or at least becoming so easy to split that it can no longer be mounted without being damaged. Accumulators with separators according to the invention, on the contrary, can be mounted dry, and can therefore be stored for long periods, either charged or not, without their capacity being appreciably impaired.

What we claim is:

1. A three layer separator for electric accumulators, said separator comprising an intermediate layer and two facing layers applied to opposite sides of said intermediate layer, one of said facing layers consisting of a non-splitting acid-resistant microporous filter plate made from a material selected from the group consisting of polyvinyl chloride fibers, polystyrene fibers, fabric formed from polyamide fibers, fabric formed from polyester fibers, hard rubber, glass fabric, impregnated paper, paper reinforced with glass fibers and webs formed from asbestos fibers, the other of said facing layers consisting of a glass mat, said intermediate layer being a perforated and corrugated plate formed from a material selected from the group consisting of polyvinyl chloride plastic and hard rubber, and said three layers being united solely by being sewn together along at least one seam passing through and extending longitudinally along a corrugation of said intermediate layer.

2. A separator for electric accumulators as defined in claim 1 wherein said layer of filter material is likewise provided with corrugations, the corrugations of said layer of filter material being of the same distance apart as the corrugations in said intermediate layer and nested within the latter, and the height of said corrugations in said layer of filter material being less than one-half the height of the corrugations in said intermediate layer.

3. A separator for electric accumulators as defined in claim 1 and which further includes reinforcing needles of acid-resistant material disposed within and extending longitudinally of the corrugations in said intermediate layer.

4. A separator for electric accumulators as defined in claim 3 wherein said needles are secured to the corrugations in said intermediate layer along which they extend.

5. A separator for electric accumulators as defined in claim 3 wherein said needles extend beyond at least one of the edges of said separator.

6. A separator for electric accumulators as defined in claim 1 wherein at least one of the corrugations in said intermediate layer has a substantially rectangular configuration and is not perforated, and said sewing seam extends along said rectangularly configured corrugation.

7. A separator for electric accumulators as defined in claim 6 wherein said layer of filter material is likewise provided with a corrugation nested within said rec-

tangulyarly configured corrugation of said intermediate layer.

8. A separator for electric accumulators as defined in claim 1 wherein the edge portions of said intermediate layer which extend parallel with the corrugations thereof are non-corrugated and lie close against the surface of said layer of filter material.

9. A separator for electric accumulators as defined in claim 8 wherein the corresponding edge portions of said layer of filter material are folded over the said edge 10 portions of said intermediate layer.

10. A separator for electric accumulators as defined in claim 1 wherein one of the edges of said intermediate layer lying at a right angle to the direction of corrugation is provided with a reinforcement.

11. A separator for electric accumulators as defined in claim 10 wherein said reinforcement for the edge of said intermediate layer is established by a reinforcing member fitted to said edge,

12. A separator for electric accumulators as defined in claim 10 wherein said reinforcement for the edge of said intermediate layer is established by doubling over a portion of said edge.

13. A three layer separator for electric accumulators,

said separator comprising an intermediate layer and two facing layers applied to opposite sides of said intermediate layer, one of said facing layers being constituted by a microporous polyester resin fabric, the other of said 5 layers consisting of a glass mat, said intermediate layer being perforated and corrugated and formed from polyvinyl chloride, and said three layers being united solely by being sewn together along at least one seam passing through and extending longitudinally along a corrugation of said intermediate layer.
